[57] CLAIM

The ornamental design for a machine for cleaning bowling balls and shoes, as shown and described.

DESCRIPTION

FIG. 1 is a perspective view of a machine for cleaning bowling balls and shoes with the top sliding door fully closed, showing my new design;

FIG. 2 is a partial perspective view thereof with the sliding door fully opened;

FIG. 3 is a top plan view thereof with the sliding door fully closed;

FIG. 4 is a side elevation view thereof, the other side being a mirror image; and

FIG. 5 is a front elevation view thereof.

The undisclosed rear is flat and unadorned.

FIG. 1

FIG. 2

FIG. 3

FIG. 4

FIG. 5
